1

The present invention relates to devices for accelerating electrons to high velocity and high energy levels which are useful in general nuclear research activities, therapy and radiography.

One type described in U. S. Patent No. 2,103,303 to Steenbeck that has proven quite satisfactory in the past few years operates on the principle of magnetic induction and is popularly referred to as a "betatron" or "ray transformer." It is comprised generally of an annular evacuated tube into which electrons are periodically injected from an electron gun type of cathode in timed relation to a magnetic system that produces a magnetic field varying comparatively slowly with time (i. e. of the order of 50 cycles/sec.) and having a space distribution such that the electrons are accelerated by the field along a circular orbit. The magnetic field divides into two components. One of these known as the "inducing field" is established in a central core arranged coaxially with the tube and effects the electron acceleration; the other known as the "control field" is established in annular pole pieces arranged above and below the tube and exerts a centripetal force upon the electrons to offset the centrifugal forces resulting from the motion around the circular path.

Due to the small mass of the electrons, the latter have been found to attain about 98% of their maximum possible speed, i. e. the speed of light by the time their energy has reached the two million electron volt level. Additional energy applied to the electrons thereafter is not therefore manifested so much in increased velocity but rather mostly as an increase in mass of the electron. The mass of the electron does not begin to increase appreciably until the velocity curve begins to level off rather flatly at about 95% of the maximum. Thereafter, the mass rises steadily with an increase in applied energy so that when the electron has reached an energy level of about 100 million volts, its mass will have been increased to about 197 times over that which it had at rest.

One disadvantage of the betatron is that the size of the magnetic structure which carries the magnetic field varies with the energy level desired to be reached. Hence the higher the final energy level the larger and more expensive becomes the magnetic structure.

To overcome this disadvantage, it has been proposed to modify the betatron by incorporating a high frequency gap in the annular tube and using the effect of the oscillating electrostatic field produced across the gap in combination with the time varied control field to impart additional

2

energy to the electrons after the latter have been initially accelerated to an energy level of about two million electron volts by the magnetic induction principle of the betatron at which time the inducing field core saturates and betatron action ceases. An electron accelerator operating on these combined principles is now commonly known as a "synchrotron."

In the synchrotron the frequency of the gap is 10 of course determined by the radius of the electron orbit since its period must correspond to the time required by the electron stream to make one revolution around its orbit. During the initial phase of the acceleration, the electrons are 15 spread around the orbit but when the high frequency field is switched in, the electrons become bunched together and all reach the gap when the far side thereof is charged positively and are thereby drawn across the gap with an attendant 20 gain in energy. Thereafter, the electrons gain incrementally in energy each time they complete a revolution around their orbit and recross the high frequency gap and finally are diverted from the orbit to be used for the particular purpose desired.

When the high frequency field is operating, the 25 system is practically self-stabilizing and the electrons will remain locked in phase with the field so far as their time of arrival at the gap is concerned. Thus, for example, should any electron 30 tend to arrive late at the gap and consequently receive too little energy, the magnetic control field will urge the electron radially inward from the normal orbit and it will then follow a path of less radius, for the next revolution. However, 35 because of the smaller path radius it will arrive at the high frequency gap sooner than the other electrons and consequently receives more than its share of energy from the field with the result that the next time around the orbit the path 40 radius will tend to increase thus returning the electron closer to its normal orbital path.

A similar stabilizing action takes place in the 45 event that an electron riding the normal orbit arrives too early at the gap and receives more energy than it should. Its path radius then tends to increase during the next revolution with the result that it tends to arrive late at the gap, receives less than its share of the increase in energy and the magnetic control field pushes it back in the direction of the normal orbit.

The synchrotron which has been described above has, however, one serious operating disadvantage which stems from the fact that the 50 central core of the magnetic structure ap-

proaches saturation as the magnetic flux through it increases with time to impart accelerating forces to the electrons. Because of this saturation characteristic, the inductance of the energizing winding has an unavoidable variable 5 characteristic and thus the variable wattless power taken by it cannot be entirely compensated out through use of a bank of condensers since the latter cannot, in any practical manner, be likewise given a correspondingly variable 10 capacity characteristic. One solution to the problem has been to load the relatively low frequency alternating current source feeding the energizing winding for the synchrotron's magnetic structure with comparatively high amplitude currents that originate from harmonics of much higher frequency. However, these harmonics cause large losses and large drops in voltage and likewise a considerable increase in the wattless power requirements of the system. 15

The object of this invention is to provide an improved construction for the magnetic structure of the synchrotron which makes it possible to overcome the disadvantages inherent in the conventional construction wherein both the inducing and control magnetic fields are produced from the same winding. According to the present inventive concept, the relatively low frequency power source is used only for the purpose of providing the time varied magnetic control 20 field component for keeping the electrons on their orbit, and the magnetic inducing field essential to betatron operation is supplied by a current of a relatively higher frequency.

Several practical constructions embodying the inventive concept are illustrated in the drawings. Fig. 1 is a view in vertical central section of one embodiment; Fig. 2 is a plot of magnetic flux curves related to the Fig. 1 construction; Fig. 3 is likewise a view in vertical central section of a slightly modified construction; Fig. 4 is a plot of magnetic flux curves related to the Fig. 3 construction; and Figs. 5 and 6 are views in half central vertical section illustrating modifications of the Fig. 3 construction.

With reference now to Fig. 1, the synchrotron is seen to include a cylindrical array of substantially C-shaped laminated plates 1 of magnetic material, a toroidally shaped, evacuated glass tube 2 located between the confronting annular pole faces 3-3' formed by the inner legs 4, 4' of the C-shaped plates, and an energizing winding split into two annular coil sections 5, 5' located in the space between the inner legs 4, 4' and the outer legs 6 which form the yoke for completing the closed path of the magnetic flux through the plates.

The coil sections 5-5' which are arranged in series are connected to a source 7 of alternating current of relatively low frequency of the order of 50 cycles/sec., and a wattless power condenser 8 is connected across the coils 5-5'.

Electrons are emitted periodically in timed relation with the time-varied magnetic field set up in the magnetic structure from an electron gun 9 located to one side of the orbit k in tube 2 along which the electrons are to be accelerated, and the tube 2 includes an oscillator driven resonant cavity section which provides a high frequency gap across which the electrons are pulled each revolution for increasing their energy after the initial acceleration by the magnetic induction principle (betatron operation) has terminated. However, since neither the specific construction of the cavity nor the

manner for switching in the same are of concern here insofar as the present invention is concerned they have accordingly not been included in the interest of simplifying the drawings. One practical form, however, is shown and described in an article entitled "Atomic Artillery" that appears in the June 1947 issue of the General Electric Review.

In the normal construction for a betatron type of accelerator, the magnetic structure also includes a central core extending axially along the axis A-A in which the inducing field is produced by the magnetizing coils. However, in Fig. 1 it will be observed that due to the C-shaped configuration of the laminated plates 1, the magnetic structure when assembled from the plates establishes an axial, cylindrically shaped opening 10. Consequently, the coils 5-5' are used only for the purpose of establishing the control field across the confronting annular pole faces 3-3' which maintains the electrons on the orbit k .

In accordance with the present invention, the inducing field at higher frequency is set up in a 25 separate magnetic structure 11 which as illustrated has the form of a hollow rectangle made up from laminated plates. One leg 11a of the core passes axially through the opening 10 and has a coil 12 wound thereon which is connected in series with the energizing coils 5-5'. The winding 12 has the same number of turns as coils 30 5-5' combined and its winding direction is opposite to that of the coils 5-5' thus establishing a magnetic field which not only opposes or 35 "bucks" the field produced by coils 5-5' but is of the same magnitude so as to prevent the latter from setting up any inducing field component in the separate core leg 11a. Thus the control field and the inducing field are maintained entirely independent of one another. Consequently the control field which threads the tube 2 between poles 4-4' closes through the outer legs 40 6 as indicated by the flux path ϕ depicted in Fig. 1.

45 The inducing field to be set up in the core leg 11a is produced by a coil 13 which surrounds leg 11b of the separate core 11. Coil 13 is connected via switch 14 to a source 15 of alternating current of the same phase and frequency as the source 50 7 and a condenser 16 is connected across the source 15. Although for simplicity in illustration, switch 14 is illustrated as being of the blade type, the switch in practice would be of the thyratron or similar type as shown in Fig. 3 and so 55 controlled that it closes at the instant when the magnetic control flux produced in the control poles 4-4' passes through the zero point in its cycle and at which instant the electron stream is injected into the tube. This zero point on the control flux curve occurs when the voltages at the sources 6 and 15 reach their maximum value. Condenser 16 which in the meantime has been charged from source 15 while switch 14 was open, now discharges through winding 13 with a frequency determined by the capacity of condenser 65 16 and inductance of coil 13 and produces in the core 11, and particularly the core leg 11a, the magnetic flux ϕ which serves as the inducing field component for effecting initial acceleration of the electron stream.

70 As is evident from the plot of curves in Fig. 2, the wavelength of the inducing field, i. e. magnetic flux ϕ curve set up in the core 11 is about one fourth that of the control field, i. e. magnetic flux curve ϕ_1 , is constituted by a succession

of pulses having a repetition rate equal to the frequency of the control field and attains a much lower maximum amplitude. However, in the neighborhood of the zero point on the flux curves, both fluxes ϕ and ϕ_1 have substantially the same slope and vary in like manner with time, so that in this neighborhood, the necessary 1:2 relation between the control and inducing field components essential to operation on the betatron principle, and which is explained in the aforementioned Steenbeck patent, can be established without difficulty through proper selection of the peak amplitude of the voltage at source 15 and the capacity of condenser 16.

Fig. 3 shows another practical construction for a synchrotron embodying the principles of the invention. In this modification which is adapted to accelerate electron streams in opposite directions around orbit k on successive halves of the alternating current wave applied to the energizing coils, the magnetic structure of the synchrotron differs from that shown in Fig. 1 in that the central leg 18 in which the inducing field is produced is structurally united with the control poles 19-19' by means of inner yokes 20-20' in addition to the outer yokes 21. The central leg 18 is surrounded by a coil 22 and the latter contains a few less turns than the magnetizing coils 23-23' to assure that none of the flux produced by the latter coils closes through the central leg 18. That is, all of the flux which passes through the control poles 19-19' is returned via the outer yokes 21 only.

Coils 22 and 23-23' are arranged in series and connected to a source of alternating current 24 of relatively low frequency, and a wattless power condenser 25 is connected across the coils in the same manner and for the same purpose as condenser 8 in the Fig. 1 construction.

The circuit for producing the higher frequency current for establishing the inducing field in the central leg 18 is comprised of an autotransformer 26 connected across the alternating current source 24, a condenser 27 connected for energization periodically from the autotransformer, and a pair of thyratron tubes 28, 29 connected in parallel and arranged in front-to-back relation for periodically discharging the condenser 27 through coil 22. Condenser 27 thus corresponds in function to condenser 16 in Fig. 1.

For switching in the thyratrons alternately at the proper instant in each half wave of the magnetic control flux produced in the control poles 19-19' by coils 23-23', a saturable core peaking transformer 30 is utilized. The latter includes a primary winding 31 on core 32 connected in series with coils 22, 23-23' and two secondary windings 33, 34, wound in relatively opposite directions. One side of winding 33 is connected through a direct current biasing battery 35 to the cathode 28a of thyratron tube 28 and the other side thereof to the control grid 28b of such tube; the grid 29b and cathode 29a of thyratron 29 are connected in a similar manner through biasing battery 36 to the terminal ends of the transformer secondary 34.

Operation of the arrangement shown in Fig. 3 is the same in principle as that illustrated in Fig. 1 except that the former is adapted to operate on both halves of the magnetizing flux wave as previously mentioned. Referring now to the curves plotted in Fig. 4, the flux wave through the control poles 19-19' and which is produced by coils 23-23' is designated by curve ϕ_3 . As this wave passes through the zero point at time

t , at which time a stream of electrons is injected from cathode 37, transformer 30 will unsaturate momentarily producing peaked voltages in the secondaries 33, 34 of relatively opposite polarity.

- 5 These voltages are of course impressed on the grids of the thyratrons 28-29 and since the latter are arranged front-to-back, only one of them such as tube 28, will then fire and discharge condenser 27 through the coil 22 thus producing the inducing flux ϕ_4 in the central leg 18 at the higher frequency and lower amplitude as indicated in Fig. 4.

In a similar manner, as the control field flux wave ϕ_3 next passes through zero, i. e. at the time t_1 , and at which time another stream of electrons is injected in the opposite direction from cathode 37 for acceleration in the opposite direction around tube 38, transformer 30 will again produce peaked voltages in the secondaries 33, 34 causing the other tube 29 to fire and discharge condenser 27, which in the meantime has recharged, in the opposite direction through coil 22.

It will be observed that a resistor 39 is connected in the circuit between the thyratrons 28, 29 and one side of the coil 22. The effect of this resistor is to flatten out the slope of the flux curve ϕ_4 . By making resistor 39 sufficiently large, it becomes possible to empty the condenser 27 completely of its charge each time that discharge takes place. This is especially desirable when only half wave operation of the accelerator is desired, in which case, only one thyratron switching device would then be required.

If it is desired to use the same number of turns 35 on coil 22 as are in coils 23, 23', either an inductance 40 must be connected in parallel with the winding 22 as shown in Fig. 5, or the central leg 18 must be interrupted by an air gap 41 as shown in Fig. 6. Otherwise, the magnetic structure, coils and control circuits for Figs. 5 and 6 are the same as in Fig. 3.

In conclusion, I wish it to be understood that while the constructions shown in the drawings are preferred, various changes may be made in the details particularly as to the switching circuits, without departing from the spirit and scope of the invention as defined by the appended claims.

I claim:

- 50 1. In a device for accelerating electrons to high energy levels and in which an initial acceleration to substantially the speed of light is effected through magnetic induction, the combination comprising, an annular evacuated tube providing a closed orbital path for electron travel, a magnetic structure associated with said tube and which includes a central core extending axially through said tube, a pair of control poles confronting each other on opposite sides of said tube at said orbital path and yoke means disposed radially outward of said control poles and connected therewith, a main winding surrounding said control poles and adapted to be energized by a first alternating current of relatively low frequency to produce a time varied magnetic control field in said control poles, an auxiliary winding surrounding said central core and connected in series with said main winding for producing a time varied magnetic field bucking and nullifying the magnetic field which otherwise would be produced in said central core by said main winding whereby said control field closes through said yoke means rather than through said central core, and means including winding 65 means associated with said central core arranged

for energization from a source of a second alternating current having a wavelength substantially shorter than that of said first alternating current, said second alternating current being applied to said winding means in pulse form having a repetition rate equal to the frequency of said first alternating current and which produces a time varied magnetic inducing field in said central core in phase with said magnetic control field as the latter passes through the zero point in its wave.

2. An electron accelerator as defined in claim 1 wherein said second source of alternating current is constituted by a charged condenser.

3. An electron accelerator as defined in claim 1 wherein said second source of alternating current is constituted by a charged condenser and further including a resistor connected in circuit between said condenser and the winding associated therewith.

4. An electron accelerator as defined in claim 1 wherein said second source of alternating current is constituted by the periodic discharge from a condenser and said condenser is charged from an alternating voltage of substantially the same phase as the voltage wave of the alternating current source that produces said magnetic control field.

5. An electron accelerator as defined in claim 4 wherein the said periodic discharge of said condenser is effected through a grid-controlled electric discharge valve of the thyratron type and in which the grid voltage varies with and reaches the ignition point of said valve when said time varied control field passes through zero.

6. In a device for accelerating electrons to high energy levels and in which an initial acceleration to substantially the speed of light is effected through magnetic induction, the combination comprising, an annular evacuated tube providing a closed orbital path for electron travel, a magnetic structure associated with said tube comprising a first closed body of magnetizable material providing a pair of control poles confronting each other on opposite sides of said tube at said orbital path, yoke means disposed radially outward of said control poles and connected therewith, a central core extending axially through said tube and which constitutes one leg of a second closed body of magnetizable material structurally independent of said first body, a main winding surrounding said control poles adapted for energization by a first alternating current of relatively low frequency to produce a time varied magnetic control field in said control poles, an auxiliary winding surrounding said central core and connected in series with said main winding for producing a time varied magnetic field bucking and nullifying the magnetic field which otherwise would be produced in said central core by said main winding whereby said control field closes through said yoke means rather than through said central core, and a third winding on said second body of magnetizable material arranged for periodic energization by a second alternating current having a wavelength substantially shorter than that of said first alternating current, said second alternating current being applied to said winding means in pulse form having a repetition rate equal to the frequency of said first alternating current and which produces a time varied magnetic inducing field in said central core in phase with said magnetic control field as the latter passes through the zero point in its wave.

7. In a device for accelerating electrons to high energy levels and in which an initial acceleration to substantially the speed of light is effected through magnetic induction, the combination comprising, an annular evacuated tube providing a closed orbital path for electron travel, a unitary magnetic structure associated with said tube comprising a central core extending axially through said tube and provided with an air gap and a pair of confronting control poles disposed on opposite sides of said tube at said orbital path, yoke means disposed radially outward of said control poles, a main energizing winding surrounding said control poles and adapted to be energized from a first relatively low frequency alternating current to produce a time varied magnetic control field in said control poles, an auxiliary winding surrounding said central core, said auxiliary winding having the same number of turns as said main winding and connected in series therewith for producing a field in said core bucking and nullifying the field which otherwise would be produced in said core by said main winding whereby said control field closes through said yoke means rather than through said central core, a second alternating current having a wavelength substantially shorter than that of said first alternating current and switching means actuated in timed relation with said first alternating current for applying said second alternating current to said auxiliary winding in pulse form having a repetition rate equal to the frequency of said first alternating current and which produces a time varied magnetic inducing field in said central core in phase with said magnetic control field as the latter passes through the zero point in its wave.

8. In a device for accelerating electrons to high energy levels and in which an initial acceleration to substantially the speed of light is effected through magnetic induction, the combination comprising, an annular evacuated tube providing a closed orbital path for electron travel, a unitary magnetic structure associated with said tube comprising a gapless central core extending axially through said tube, a pair of confronting control poles disposed on opposite sides of said tube at said orbital path and yoke means disposed radially outward of said control poles, a main energizing winding surrounding said control poles and adapted to be energized from a first relatively low frequency alternating current source to produce a time varied magnetic control field in said control poles, an auxiliary winding surrounding said central core, an inductance connected in parallel with said auxiliary winding, said auxiliary winding having the same number of turns as said main winding and connected in series therewith for producing a field in said core bucking and nullifying the field which otherwise would be produced in said core by said main winding whereby said control field closes through said yoke means rather than through said central core, a second source of alternating current having a wavelength substantially shorter than that of said first alternating current and switching means actuated in timed relation with said first alternating current for applying said second alternating current to said auxiliary winding in pulse form having a repetition rate equal to the frequency of said first alternating current and which produces a time varied magnetic inducing field in said central core in phase with said mag-

netic control field as the latter passes through the zero point in its wave.

9. In a device for accelerating electrons to high energy levels and in which an initial acceleration to substantially the speed of light is effected through magnetic induction, the combination comprising, an annular evacuated tube providing a closed orbital path for electron travel, a unitary magnetic structure associated with said tube comprising a gapless central core extending axially through said tube, a pair of confronting control poles disposed on opposite sides of said tube at said orbital path and yoke means disposed radially outward of said control poles, a main energizing winding surrounding said control poles and adapted to be energized from a first relatively low frequency alternating current source to produce a time varied magnetic control field in said control poles, an auxiliary winding surrounding said central core, said auxiliary winding having a few less turns than said main winding and connected in series therewith for producing a field in said core bucking and nullifying the field which otherwise would be produced in said core by said main winding whereby said control field closes through said yoke means rather than through said central core, a second source of alternating current having a wavelength substantially shorter than that of said first alternating current and switching means actuated in timed relation with said first alternating current for applying said second alternating current to said auxiliary winding in pulse form having a repetition rate equal to the frequency of said first alternating current and which produces a time varied magnetic inducing field in said central core in phase with said magnetic control field as the latter passes through the zero point in its wave.

10. In a device for accelerating electrons to high energy levels and in which an initial acceleration to substantially the speed of light is effected through magnetic induction, the combi-

nation comprising, an annular evacuated tube providing a closed orbital path for electron travel, a magnetic structure associated with said tube and which includes a central core extending axially through said tube, a pair of control poles confronting each other on opposite sides of said tube at said orbital path and yoke means disposed radially outward of said control poles, a main winding surrounding said control poles and adapted to be energized by a first alternating current source of relative low frequency to produce a time varied magnetic control field in said control poles, an auxiliary winding surrounding said central core and connected in series with said main winding for producing a time varied magnetic field bucking and nullifying the magnetic field which otherwise would be produced in said central core by said main winding whereby said control field closes through said yoke means rather than through said central core, and means associated with said central core arranged for energization of said core with a second alternating current having a wavelength substantially shorter than that of said first alternating current and switching means actuated in timed relation with said first alternating current for applying said second alternating current to said auxiliary winding in pulse form having a repetition rate equal to the frequency of said first alternating current and which produces a time varied magnetic inducing field in said central core in phase with said magnetic control field as the latter passes through the zero point in its wave.
